UNITED STATES PATENT OFFICE.

JACOB S. WALCH, OF WALLA WALLA, WASHINGTON.

PILOT-CONTROLLED TORPEDO.

1,188,515.

Specification of Letters Patent. Patented June 27, 1916.

Application filed October 12, 1915. Serial No. 55,373.

To all whom it may concern:

Be it known that I, JACOB S. WALCH, a citizen of the United States, residing at Walla Walla, in the county of Walla Walla 5 and State of Washington, have invented certain new and useful Improvements in Pilot-Controlled Torpedoes, of which the following is a specification.

This invention relates to improvements 10 in self-propelled torpedoes which enable them to be controlled by an attendant or pilot until within short striking distance of the enemy's vessel.

Heretofore self-propelled torpedoes, usually referred to as automobile torpedoes, have been entirely controlled by self-contained automatic mechanism, the steering being usually under the control of a gyroscope device which maintains it upon the 20 course determined by the aim of the launching tube on the torpedo boat or submarine from which it was ejected. If discharged from the latter they must travel through the water for a distance of at least half a 25 mile and a distance of from five to seven miles if launched from a battleship during an engagement. The chances of missing the mark are, therefore, very good.

Torpedoes have been mainly driven by 30 compressed air used as a motive fluid actuating a turbine or other engine which actuates the propellers. More recent developments using engines of the internal combustion type supplied with an operating fluid, generally supplied from a spray of gasoline or alcohol atomized by a stream of combustion-supporting gas from a tank of compressed air or oxygen, have increased the range of action.

All of these improvements, however, fail to 40 overcome the inherent defect in the automobile torpedo, viz: the necessity for accurate aim while it is being launched. To overcome this greatest obstacle to the success of this method of warfare, it has been proposed 45 to direct the course of the torpedo externally by wireless electric means which introduces the necessity of being able to see the enemy, or to provide the torpedo internally with sound responsive control mechanism which, 50 however, is evidently of limited application.

The main object of my present invention is to overcome the difficulties above enumerated by incorporating in the torpedo of the self-propelling type, a detachable element or 55 portion within which an attendant or pilot

may accompany the main body of the torpedo for any desired distance during which time he may control its movements and then at will cause the pilot section to be detached, leaving the main torpedo body to proceed 60 under its own automatic control. In this manner the torpedo may be launched from a vessel many miles distant and entirely out of sight and range of the enemy and be directed by the pilot until within definite 65 striking range.

Having thus given a general statement of the object and purposes of this invention, I will refer for a more detailed explanation to the accompanying drawings, in which— 70

Figure 1 is a side elevation of a torpedo embodying my invention; Fig. 2 is an enlarged vertical section on the line 2—2 of Fig. 5; Figs. 3 and 4 are side and end elevations respectively, of the detachable pilot section; Fig. 5 is a longitudinal section of the torpedo with the pilot section in position; Fig. 6 is an enlarged detail on the line 6—6 of Fig. 5; and Figs. 7 and 8 are enlarged detail views of certain parts. 80

I have illustrated my invention applied to a torpedo of the usual cigar-shaped body with a depending keel portion 2, the forward end 2' tapering toward the nose or pointed bow 3. The forward end 3, constitutes the "war-head" and carries the explosive charge, as usual. The main body or casing 6, contains the storage tank 7, for the liquid fuel and the tank 8, for the combustion-supporting gas under high pressure. The chamber 90 10, may contain ballast and the chamber 12, a storage battery to actuate a starting motor 14, and the spark coil for the internal combustion engine 15. 85

When the torpedo is traveling on the surface of the water, partly submerged, as illustrated in Figs. 1 and 4, the air used by the engine may be taken from the air-chamber 18, which is in communication with the atmosphere through the tubes 20, and the air 100 may be supplied in this manner when the torpedo is slightly submerged so long as the air intake tubes extend above the water line indicated by dotted line x—x. When the torpedo is to be submerged to a greater depth, the tubes 20 are lowered into dotted line position, by any suitable means under control of the pilot, as by rack 23 and pinion 24, this movement cutting off the air by a suitable valve in the sleeve 25, and the engine is then 105 110

supplied with gas from the compressed gas tank 8, exhausting in any suitable manner, as through the hollow shaft 26 of the propeller 28.

- 5 In order that the torpedo may be steered and controlled by a pilot from the time it is launched from a vessel until arriving within a sure striking distance of the enemy's vessel, I provide a detachable element or pilot-
0 carrying portion which may be variously secured to the main casing or body of the torpedo. I have shown, for purpose of illustration, a detachable auxiliary casing 30, which I may term a pilot-section, provided with a tubular end 31 adapted to telescope into a corresponding recess or socket in the rear end of the torpedo, the pilot-section being detachably held in position in any suitable manner. As conventionally
5 illustrated in Fig. 4, the various levers or controlling devices 34, 35, etc., for operating the rudder 36, controlling the engine actuating the various valves and other operating parts, are arranged within reach of the
0 hands of the pilot, who has a clear range of the horizon through the several ports 37 in the conning hood 38.

The depth of submergence may be regulated by the inclination of the pivoted end sections 41, 42 of the planes 40 at the sides of the body. These may be controlled in any suitable manner. For illustration, I have shown the shafts 41' and 42' upon which the pivoted sections 41, 42, are carried, as being provided with pinions engaging a rack bar 45, actuated through a nut on the worm 46, controlled through intermediate connections by the wheel 35. It is necessary, of course, that the controlling rods and levers leading into the pilot section should be separable to permit the latter to be disconnected from the main body or casing. I have, therefore, shown each of the stems or rods provided with separable tongue and socket connections, such as shown at 48 in Fig. 8.

When the pilot has brought the torpedo into proper striking distance of the enemy's vessel, and having fixed the control for the correct course and the proper submergence, so that the torpedo will proceed in a manner to strike the vessel, he operates the rod 50 to open the valve 51 in the pipe 52, permitting pressure from the compressed air-tank 54 to enter the chamber 56, between the wall 57 of the torpedo casing and the piston 58, and causing the latter to eject the pilot-section from the main body of the torpedo. The piston is caught at the end of its rearward stroke by suitable latches 60, thus closing the recess from which the pilot-section was ejected and preventing any ingress of water which would tend to disturb the equilibrium of the torpedo. As soon as the pilot-section is free from the main body of the torpedo, the weight of the conning-portion 38, causes

the section to turn over, the portion 38 then serving as an efficient keel. The pilot may then open the hatch-way 61, and by means of oars, as indicated in Fig. 3, maneuver back to his vessel or wait until he is 70 picked up.

From the above description it will be apparent that I have completely overcome the disadvantages of the automobile or self-propelled torpedo by reason of its restricted 75 range of action and have provided means whereby the submersible torpedo may have any desired range. It is no longer necessary to be within striking distance, nor to discharge the torpedo with a definite aim. The 80 pilot-controlled torpedo may be launched from a vessel entirely out of range of the enemy's guns. I have also provided the proper element of safety for the pilot.

While I have described in detail the construction illustrated in the accompanying drawings for the purpose of disclosing an embodiment of my invention, I am aware that various changes and modifications can be made within the scope of the appended 90 claims and within the spirit of my invention. It is evident also that I am not restricted to the particular type of torpedo which I have adopted for purposes of illustration.

95 I claim:—

1. A torpedo, comprising a main casing or body, mechanism for propelling and for steering said body, an auxiliary casing detachably secured to said body and having an 100 inclosed chamber adapted to hold an attendant or pilot, and controlling means connecting said mechanism with said chamber whereby the operator may control the operation of the torpedo.

2. A torpedo, comprising a main casing or body, mechanism for propelling and controlling the movements of said body, means for manually controlling said mechanism, an auxiliary casing detachably secured to said 110 body and having an inclosed chamber adapted to hold a pilot, and controlling means connecting said mechanism with said chamber whereby the pilot may control said mechanism.

3. In combination with a self-propelled submarine torpedo, a detachable section having an inclosed chamber adapted to hold a pilot, auxiliary controlling means connecting the operating mechanism of the torpedo 120 with said chamber to permit the manual control thereof by the pilot, and pressure-actuated mechanism under the control of the pilot for ejecting said section from the main body of the torpedo.

4. A self-propelled submarine torpedo having a main casing provided with a chamber or recess therein, a detachable section having an inclosed chamber adapted to hold a pilot and telescoping into said recess, 130

means under the control of the pilot for expelling said detachable section from the main casing.

5. A self-propelled submarine torpedo having a main casing and a detachable auxiliary casing telescoping therewith, the latter having an inclosed chamber to hold a pilot, means for controlling the operation

of the torpedo within said chamber, and means for disconnecting the main and auxiliary casings. 10

In testimony whereof I affix my signature in presence of a witness.

JACOB S. WALCH.
